UNITED STATES PATENT OFFICE.

JAMES L. SCROGGINS, OF ALHAMBRA, CALIFORNIA.

STREET INDICATOR OR ANNUNCIATOR.

Application filed December 11, 1920. Serial No. 429,976.

To all whom it may concern:

Be it known that I, JAMES L. SCROGGINS, a citizen of the United States, residing at Alhambra, in the county of Los Angeles and State of California, have invented new and useful Improvements in Street Indicators or Annunciators, of which the following is a specification.

This invention relates to improvements in street indicators or annunciators for street cars and more particularly to improvements in the street indicator or annunciator as disclosed in Letters Patent 1,350,038 issued August 17, 1920.

An object of the invention is to provide means for positively arresting movement of the indicia working web at predetermined intervals to prevent its moving too far upon each operation, and, thereby insuring proper exhibiting of each station indicating sign.

Other objects of the invention will appear in the following detailed description and in the accompanying drawings wherein:

Fig. 1 is a section showing parts in elevation through the improved street indicator or annunciator.

Fig. 2 is a transverse vertical section through the improved indicator or annunciator.

Fig. 3 is an enlarged fragmentary view in side elevation of the improved indicator or annunciator.

Referring more particularly to the drawings the improved indicator includes a supporting structure 1 which is adapted to be enclosed in a suitable casing as disclosed in the Letters Patent heretofore referred to. The improved indicator or annunciator comprises a pair of web rollers 2 and 3 which have an indicia carrying web 4 connected thereto and adapted to be wound thereon. The roller 2 has an energy storing structure 5, preferably, comprising a coil spring connected thereto, the function of which is more specifically disclosed in the Letters Patent No. 1,350,038. However, in the present embodiment of the invention the energy storing structure 5 is connected to the shaft 6 which carries the roller 2 by a gear 7 and pinion 8.

The lower roller 3 is rotated for unwinding the web 4 therefrom or winding it thereon, by the operation of the solenoid 9 the central armature 10 of which has an angle lever 11 pivotally connected thereto. The lever 11 is pivoted at its elbow to a suitable

supporting bracket as shown at 12 and it engages beneath a transversely extending lip 13 formed upon the sliding bar 14. The bar 14 is slidably supported by a suitable guide 15 and its lower end is pivotally connected to pawls 16 and 17 which co-act with a ratchet 18 mounted upon the shaft 19 which is connected to the roller carrying shaft 20 by a gear 21 and pinion 22. As clearly shown in Fig. 2 of the drawing the pawls 16 and 17 are oppositely disposed, and are adapted to rotate the shaft 19 in opposite directions when they are moved into operative relation with the ratchet 18 by operation of the lever 23. The lever 23 is connected to the pawls 16 and 17 by suitable links 24 so as to permit movement of either of the pawls into operative position, depending upon the direction of movement of the lever 23. If so desired the lever 23 may be moved into a neutral position at which time both of the pawls 16 and 17 are held out of operative relation with the ratchet 18 and the shaft 20 and roller 3 carried thereby, may be manually rotated by means of the thumb screw 24 to manually wind the web 4 upon the roller 3 or unwind it therefrom as desired.

To prevent movement of the web 4 too far upon each operation thereof under the energizing of the solenoid 9, a cam 25 is mounted upon the shaft 20 and is provided with circumferentially spaced notches 26 in which the tongue 27, formed upon the escapement lever 28, is adapted to engage, for instantly arresting rotation of the roller 3 and consequently permitting accurate adjustment of the web 4 to bring the station indicating sign in proper alignment with the exhibiting window. The lever 28 is pivotally mounted upon a stud 29 and a lateral projection 30 is carried by the guiding bar 14 and engages beneath a pawl 31 carried by the escapement lever 28 for arresting the lever to move the tongue 27 out of one of the notches 26 to permit rotation of the shaft 20 and roller 3. Yieldable engagement between the projection 30 and lever 28 is had by means of the pawl 31 which is pivotally connected as shown at 32 to the escapement lever 28 and is held in operative relation to the projection 30 by a flat spring 33. A return spring 34 is connected to the escapement lever 28 for returning it to move the tongue 27 into subsequent notch 26 as the guide 14 moves

downwardly to its normal position under action of its return spring 33. Should the tongue 27 be returned prior to the positioning of a notch 26 in tongue receiving position the tongue will engage and ride over the perimeter of the cam disc 25 moving into the first notch 26, and thereby arresting rotation of the shaft 20 and roller 3.

The upward movement of the guiding bar 14, through the contacting engagement of the projection 30 with the pawl 31, will raise the lever 28 to bring its tongue 27 out of one of the notches 26 in the cam 25. When the bar 14 travels upwardly a predetermined distance, the projection 30 will swing the pawl 31, on its pivot to an arc of almost 90 degrees and thereafter free itself of engagement with said pawl. This permits the spring influenced lever 28 to be moved to initial position to bring its tongue 27 on to the periphery of the cam 25 so that the said tongue will again ride into one of the notches 26 to halt the turning of the roller 3. In the downward movement of the bar 14 the projection 30 will ride against the inclined face of the pawl and when the said projection 30 is brought directly below the said pawl the spring 33 will swing the pawl to arrange the under face thereof over the said projection 30.

The conductors for the solenoid are indicated by the numerals 50.

The energizing of the solenoid 9 may be controlled by a suitable circuit closing device of any approved construction as described in Letters Patent 1,350,038 and when the solenoid 9 is energized the movement of its central armature 10 will rock the angle lever 11. The rocking of the lever 11 will move the sliding bar 14 which will in turn operate the pawls 16 and 17 and ratchet 18 for rotating the shaft 19. The rotation of the shaft 19 will through the medium of the pinion 22 and gear 21 rotate the roller carrying shaft 20 for moving the web 4 to bring the proper sign into exhibition. Excessive rotation of the web carrying rollers is prevented by means of the cam disc 25, tongue 27 and escapement lever as heretofore described.

It is, of course, to be understood that the invention may be constructed in various

other manners and the parts associated in different relations and, therefore, I do not desire to be limited in any manner except as set forth in the claims hereunto appended.

Having thus described my invention what I claim is:

1. A street annunciator comprising a pair of web carrying rollers, a ratchet operatively connected to one of said rollers, a pair of oppositely disposed pawls for engagement with said ratchet, a manually operated lever for shifting said pawls to move one or the other of them into engagement with said ratchet, a slidable bar for operating the pawls to in turn rotate said ratchet, a transversely extending lip carried by said slidable bar, a pivotally mounted bell crank lever having one end engaging said lip, a solenoid connected to said lever for operating the lever to move said slidable bar longitudinally, means associated with the roller to which said ratchet is connected for limiting the rotating movement of the roller, and energy storing means associated with the web carrying roller other than the one to which said ratchet is connected.

2. A street annunciator comprising a pair of web carrying rollers, a ratchet operatively connected to one of said rollers, a pair of oppositely disposed pawls for engagement with said ratchet, means for shifting said pawls to move one or the other of them into engagement with said ratchet, a slidable bar for operating the pawls to in turn rotate said ratchet, a transversely extending lip carried by said bar, a pivotally mounted bell crank lever having one end engaging said lip, a solenoid connected to said lever for operating the same to impart movement to the slidable bar, a cam rotated through the action of the bar, having spaced notches therein, an escapement lever having a tongue to engage said notches, and means operatively connecting the bar and lever to intermittently engage the tongue with the notches.

In testimony whereof I affix my signature.

JAMES L. SCROGGINS.
